cut

Application August 29, 1939, Serial No. 292,416

5 Claims. (Cl. 38—78)

This invention has to do with a combination flatiron and clothes dampener and is concerned primarily with a novel assembly of these mechanisms.

A conventional present day iron, particularly one which is electrically heated, ordinarily comprises an iron body having a pointed nose and a substantially square or blunt heel. The iron body carries a handle which is used in manipulating the iron, and the iron body also carries terminals or binding posts for connection with an electric cord, and a control switch for controlling the electrical heating elements within the iron body.

When clothes dampening mechanism is associated with the iron it has been found desirable to have a spray nozzle positioned substantially at or over the nose of the iron. Likewise, from the viewpoint of convenience and freedom from interference with manipulation of the iron during use it is recognized as desirable to have a water reservoir, which is an essential part of the dampening mechanism, positioned at the heel of the iron. With the location of the spray nozzle and the water reservoir fixed by these conditions of usage, it is obviously necessary to connect the water reservoir with the spray nozzle and include in the mechanism a force pump for causing the water to issue from the spray nozzle as a spray.

With the foregoing conditions in mind this invention has in view, as its foremost objective, the provision of a combination flatiron and clothes dampener of the character above noted in which the handle for the iron takes the form of a housing, and which housing receives the connections between the spray nozzle at the nose, and the reservoir at the heel.

Another important object of the invention is to provide, in a combination flatiron and clothes dampener of the character above noted, a tubular connection extending directly from the water reservoir at the heel, through the handle to the spray nozzle at the nose, and which tubular connection has associated therewith a force pump which is housed either by the tank or the handle.

In arranging clothes dampening mechanism with a flatiron in accordance with the practice above outlined the provision of an operating instrumentality for the pump is a feature of importance. It is obviously of the utmost desirability to have the operating instrumentality located at a position in which it may be readily operated by the user of the iron with the same hand that grasps the handle.

It is also highly desirable that the operating instrumentality be not of the type which is easily operated by accident. Moreover, it is desirable that the operating instrumentality be so arranged with the handle as to readily blend in with the design thereof and not take the form of

a protuberance or projecting part which might be easily damaged.

With all of these conditions in mind this invention has in view, as an object, the provision of a combination flatiron and clothes dampener of the character above noted in which the handle at the nose of the iron includes a front post that defines, with the main body portion of the handle, a nook or corner. Positioned in this nook or corner is a trigger which is operatively connected by suitable means within the handle housing to the force pump of the dampening mechanism.

Another somewhat more detailed object of the invention is the provision of an arrangement of the character above noted in which spring means are included as a part of the force pump, and which spring means normally maintain the trigger in its forward position in which it is ready for operation by having the finger of the operator press thereagainst. Upon release of pressure from the trigger the spring always returns the same to this forward position.

A further object of the invention is the provision of a combination flatiron and clothes dampener of the character above noted in which the handle includes front and rear posts which are connected by the grip portion of a handle. The rear post preferably takes the form of a hollow structure which opens into the housing defined by the grip portion of the handle. This hollow rear post preferably encloses therewithin the terminals or binding posts of the electric iron, and an electric cord passes through an opening in the side wall of the rear post and is connected to these terminals.

A further object of the invention is the provision of an arrangement such as set forth in the preceding paragraph in which the rear face of the rear handle post is open, and on which open face is mounted the water reservoir. Thus the water reservoir may be assembled with the handle of the iron in a compact and sturdy manner. This feature is of importance because the reservoir is designed to constitute a stand on which the iron may be rested in an upright position when not in use.

Various other more detailed objects and advantages such as those which arise in connection with mounting the water reservoir on the rear post of the handle, the particular arrangement of the trigger mechanism in the handle, and the positioning of the spray nozzle at the nose, will in part become apparent, and in part be hereinafter stated, as the description of the invention proceeds.

The invention, therefore, comprises a combination flatiron and clothes dampening mechanism in which the flatiron consists of an iron body having a pointed nose and a substantially

square heel, and from which iron body upstands a front handle post, a rear handle post that is hollow, and which handle posts are connected by a grip portion that takes the form of a hollow housing. The clothes dampening mechanism comprises a water reservoir that is anchored to the rear handle post, a spray nozzle that projects forwardly from the front handle post over the nose of the iron, and tubular connections that extend from the water reservoir through the handle housing to the spray nozzle. A force pump is associated with these tubular connections, and a trigger is provided at the forward end of the grip portion of the handle therebeneath for operation of the pump. The hollow rear handle post houses the electrical terminals or binding posts, and an electric cord passes through a wall of this rear handle post and is connected to these terminals.

For a full and more complete understanding of the invention reference may be had to the following description and accompanying drawings, wherein

Figure 1 is a side view partly in section and partly in elevation of a combination flatiron and clothes dampener made in accordance with the precepts of this invention,

Figure 2 is another side view partly in section and partly in elevation developing the tubular connections extending from within the water reservoir to the spray nozzle at the nose. These connections and the force pump associated therewith are shown with the iron structure and water tank removed.

Figure 3 is an enlarged detailed view of the spray nozzle, while

Figure 4 is a similar view of the end of the tubular connection which is received in the reservoir,

Figure 5 is a rear view of the water reservoir per se,

Figure 6 is a rear view of the handle of the iron with the water reservoir removed, and

Figure 7 is a side view partly in section and partly in elevation of a handle embodying one modification of the invention.

Referring now to the drawings, wherein like reference characters denote corresponding parts, and more particularly to Figure 1, the present invention is illustrated and described at it is applied to an iron of the electric type. The electric iron is shown as comprising an iron body which is referred to generally by the reference character B, and a handle which is identified in its entirety by the reference character H. The iron body B includes a lower structure 10 having an ironing surface 11.

This structure 10 has a pointed nose at 12, and a substantially square or blunt heel at 13. The iron body B also includes an upper structure 14 having a pointed nose blending in with the nose 12, and a square or blunt heel at 15 which is upraised and spaced rearwardly of the heel 13. This upper structure 14 carries, beneath the handle H, a control switch designated 16, and upstanding from the upper part 14 of the iron body B are a pair of terminals 17.

While the iron body B is made from metal, the handle H is, of course, made from some good heat insulating material such as a rubber composition or a phenol condensation product.

The handle H includes a front handle post 18 which preferably takes a slant or incline corresponding to the inclination of the pointed nose 12 so as to afford a streamline appearance. The

rear or inner face of the front post 18 is of a grooved formation providing side flanges 19 which partially receive therebetween a trigger, as will be hereinafter pointed out.

It will be noted that the front post 18 is narrower at the top where it joins in with the grip portion of the handle, and is wider at the bottom, and the same relative dimensioning of the parts is carried out in the groove formation defined by the flanges 19, the groove being narrower at the top and wider at the bottom.

One of these side walls 19 is cut out, as indicated at 20, to provide space for the insertion of the forefinger of the user's hand. This will also be explained more in detail in connection with the trigger which is to be later described. At the top the front handle post 18 is formed with an opening 21 which communicates with the grip portion of the handle.

The handle H includes a rear handle post defined by an inner wall 22, and side walls 23 and 24 (see Figure 6). It will be noted from both Figures 1 and 6 that these walls 22, 23 and 24 receive therewithin the terminals 17. As shown in Figure 6, an electric cord is designated 25, and passes through an opening 26 in the side wall 24. The insulating conductors making up the cord 25, which are designated 27, are connected to the terminals 17 in the manner shown in Figure 6.

Referring again to Figure 1, the inner wall 22 and the side walls 23 and 24 are integrally connected at the top with the grip portion of the handle which is designated 28. This grip portion 28 takes the form of a hollow housing which defines a front recess 29 which communicates both with the opening 21 in the front handle post 18, and the groove formation defined by the flanges 19. The grip portion 28, on its underface, is provided with a slot at 30 that is substantially a continuation of the groove formation defined by the flanges 19, and which slot, of course, opens into the recess 29.

Extending rearwardly of the recess 29 and the grip portion 28 is a circular bore 31 which has opening into one side thereof a small, partially circular passage 32. Just before the rear handle post the bore 31 is enlarged, as shown at 33, the enlargement being defined by a shoulder at 34. The termination of the passage 32 at one side is represented by the shoulder 35.

The rear edges of the side walls 23 and 24 are inclined and provided with faces 36 (see Figure 6), which are adapted to have a water reservoir fit snugly thereagainst, as will be hereinafter pointed out.

Extending into the walls 23 and 24 from the faces 36 are openings 37 which are threaded. These side walls 23 and 24 are connected at the bottom by a bar-like wall 38 which has a face in substantially the same plane as the faces 36. The water reservoir is also intended to snugly engage the face of this wall 38.

Referring now more particularly to Figures 1 and 5, a water reservoir is referred to in its entirety by the reference character R, and is shown as comprising a tank defined by an inner wall 39, an outer wall 40, bottom 41, top 42, and side walls 43. Extending between the inner wall 39 and the outer wall are a plurality of sleeves 44, the walls 39 and 40 being formed with openings 45 which communicate with the bores of the sleeves 44.

When the water reservoir R is in position on the iron, as shown in Figure 1, the inner wall 39 bears against the faces 36 of the side walls 23 and

24, and the corresponding face of the wall 38. Headed fastening elements 45 having threaded extremities extend through the sleeves 44 into the openings 31 and are screwed thereinto, thus securely anchoring the water reservoir R in position on the rear handle post.

It will be noted that the top wall 42 of the reservoir R is provided with a threaded opening, as shown at 46, and this threaded opening ordinarily receives a closure in the form of a threaded plug 47, and this closure may carry an air vent for the reservoir, as represented at 48.

It will be noted from Figure 1 that a portion of the inner wall 39 of the water reservoir R which is received between the walls 23 and 24 is deformed to provide an offset wall 49, which is provided with an opening 50. The edge of the wall 49 about this opening 50 is clamped between a split collar 51 (see Figures 1 and 2) and a washer 52. The split collar 51 and the washer 52 are positioned about an exteriorly threaded bushing 53, which bushing has a flange 54 engaging the washer 52.

A pump cylinder designated 55 has a bore 56 (see Figure 2) which is interiorly threaded at its open end, as shown at 57. The bushing 53 is threaded into these threads 57 to effect the clamped relationship of the wall 49 between the split collar 51 and washer 52. This pump cylinder 55 has an end wall at 63 formed with an opening at 64 through which passes a tubular member 58.

Referring now again more particularly to Figure 1 it will be noted that the pump cylinder 55 is positioned within the water reservoir R, and that the tubular member 58 extends from the closed end 63 downwardly to a point closely adjacent to the bottom wall 41 of the water reservoir. As shown more particularly in Figure 4, the tubular member 58 is threaded at its lower extremity, and screwed on this threaded extremity is a cup-shaped member 59 having an end wall formed with a small opening 60. A ball valve member 61 normally closes the opening 60, and is maintained in seated position by a spring 62 that is interposed between the end of the tubular member 58 and the ball 61. It is obvious that the ball 61 may be unseated from the opening 60 against the influence of the spring 62.

Referring now to Figure 2, the tubular member 58 extends through the pump cylinder 55 and is in spaced relation with respect to the walls thereof. Adjacent the end wall 63 the tubular member 58 is formed with a plurality of small openings 65 which establish communication with the interior of the pump cylinder. A piston of cup-shaped formation is shown at 66, and is slidable in the bore 56. A coil spring 67 is positioned within the cylinder 55 and surrounds the tubular member 58. This spring 67 bears at one end against the wall 63, and at the other is received within the recess provided by the cup-shaped piston 66. The spring 67 normally maintains the piston 66 in its outermost position with respect to the cylinder 55.

A slide sleeve 68 having a flange 9 at one end thereof encompasses the tubular member 58 and passes through the bushing 53. This sleeve 68 is slidable on the tubular member 58 and within the bushing 53, and the flange 9 engages the piston 66. Thus when the sleeve 68 is urged towards the end wall 63 of the pump cylinder 55 the piston 66 is depressed against the influence of the spring 67.

Another slide sleeve 69 is positioned about the 75

tubular member 58 and bears against one end of the slide sleeve 68.

As shown in Figure 1, the slide sleeve 69 is positioned within the enlarged bore 33 of the grip portion 28 of the handle H, while the tubular member 58 extends through the bore 31. A flexible conduit 70 is connected to the tubular member 58 adjacent the front end of the bore 31, and this flexible conduit extends across the recess 29 and through the opening 21. This flexible conduit is bent downwardly to assume an inclination corresponding to that of the nose 12 and the front edge of the handle post 18, and at its lower end carries a spray nozzle designated 71.

15 The spray nozzle 71 is shown in detail in Figure 3, and comprises a tubular stub 72 that extends outwardly from the flexible conduit 70. This flexible stub 72 has an open end which defines a valve seat 73. Positioned about the member 72 is a cup-shaped member 74 having an end wall 75 formed with a small opening 76. A ball valve member 77 is seated on the valve seat 73 and is commonly maintained in position thereon by a spring 78 that bears against the end wall 75. Pressure of fluid coming through the flexible conduit 70 may unseat the ball valve 77 from the valve seat 73 against the influence of the spring 78 to permit the ejection of spray through the opening 76.

20 However, in the absence of any pressure of fluid within the conduit 70 the spring 78 maintains the ball 77 in sealing position.

Referring now again to Figure 1, the tubular passage 32 is shown as receiving a push rod 79 which, at one end, bears against the slide sleeve 69. At the other end a disk member 80 that is pivotally mounted, as shown at 81, on a trigger member 82, bears against this push rod 79. The trigger 82 is pivotally mounted within the recess 29, as shown at 83, and has a finger grip shown at 84 designed to normally receive the forefinger of a person's hand that is grasping the grip portion 28 of the handle H.

It will be noted that forward movement of the slide sleeve 69 within the enlarged bore 33 is limited by the shoulder 34, and that the sleeve 69 will be normally maintained in position engaging the shoulder 34 by the spring 67 within the pump cylinder. Similarly, rearward movement of the push rod 79 is limited by the shoulder 35.

The operation of the above described mechanism is believed to be fairly obvious. However, it may be briefly described by noting that a person using the iron grasps the grip portion 28 of the handle H in a conveniently comfortable manner. The iron may be manipulated in its usual manner of use, and such manipulation is rendered particularly free by reason of the cord 25 coming in at the side of the rear handle post. When the user is desirous of ejecting a spray from the spray nozzle 71 to dampen clothes being ironed, he inserts his forefinger in front of the portion 84 of the trigger 82, the cut out part 20 readily permitting of this insertion.

65 The trigger 82 is now pulled rearwardly in the usual mode of operating triggers. This rearward movement causes the disk 80 to press against the front end of the push rod 79. This push rod 79 transmits the motion to the slide sleeve 69 which is urged rearwardly and in turn moves the slide sleeve 68 rearwardly. As the flange 9 of the slide sleeve 68 is in engagement with the piston 66, the latter is moved downwardly in the pump cylinder against the influence of the spring 67. This downward movement of the piston causes

a compression of the contents of the pump cylinder 55. Thus water is forced through the openings 65, out through the tubular member 58 and flexible conduit 70, out of the spray nozzle 71.

It will be remembered that the one-way valve mechanism at the lower end of the tubular member 58 prevents any return of the water to the reservoir R. Upon release of the operator's forefinger from the trigger 82 the spring 67 is rendered effective to return the piston 66 to its outermost position, which, of course, is accompanied by a return of the slide sleeves 68 and 69 and push rod 79 to their normal positions.

On outward movement of the piston 66 the check valve in the spray nozzle 71 closes the end of the tubular member 72. Thus there is an attenuation of air or creation of partial vacuum within the pump cylinder 55. This causes water to be drawn from the reservoir R, through the opening 60, past the ball valve 61 into the bore 56 of the pump cylinder, and the dampening mechanism is again in condition for having the trigger depressed when occasion demands for the spraying of clothes.

It will be noted that the reservoir R is assembled with the handle in a compact and sturdy manner. The compact arrangement provides the utmost degree in freedom of manipulation of the iron, and the positive and sturdy connection assures that the iron may be rested on the outer wall 40 of the reservoir R in an upright position when not in use, with a high degree of stability.

It will also be noted that the front handle posts 18 constitute a trigger guide for the trigger 82, which insures against accidental operation of the trigger, and further insures against damage by the trigger accidentally striking against objects during handling.

In the form of the invention illustrated in Figures 1 to 6, inclusive, and above described, the pump is shown as being positioned within the water reservoir R. It is evident, however, that the pump mechanism might well be positioned within the housing afforded by the handle H, such an arrangement being depicted in Figure 7.

Referring now to this view, it will be noted that the tubular member 58 extends into the water reservoir R in substantially the same way as described. Moreover, a split collar and washer corresponding to the parts 51 and 52 may be employed in anchoring the tubular member to the offset wall 49 of the water reservoir. However, it would be necessary to supplement these parts by the nuts shown at 85 and 86, respectively. When this arrangement is employed the pump cylinder 55 is positioned in the upper part of the rear handle posts 58 and is sprayed in exactly the same manner as has been described.

While preferred specific embodiments of the invention are hereinbefore set forth it is to be clearly understood that this invention is not to be limited to the exact constructions illustrated and described, because various modifications of these details may be provided in putting this invention into practice within the purview of the appended claims.

I claim:

1. A combination flatiron and clothes dampener comprising an iron body having a nose and a heel, a hollow handle carried by said iron body, a spray nozzle carried by said handle above said nose, a water reservoir carried by said handle over said heel, a tubular connection extending from within said reservoir through said handle

to the said spray nozzle, a pump within said reservoir and associated with said tubular connection to force water therethrough, an operating member carried by the handle, and operating connections between said operating member and said pump, said operating connections being housed within said handle.

2. A combination flatiron and clothes dampener comprising an iron body and a handle carried by said iron body and including front and rear handle posts and a grip portion, a spray nozzle carried by the handle at the front end, a water reservoir carried by the handle at the rear, a tubular connection extending from said water reservoir to said spray nozzle, a pump arranged to force water through said tubular connection, the front handle post and grip portion of the handle defining a corner, and a trigger pivotally mounted on the grip portion of the handle and located in said corner, and connections between said trigger and said pump.

3. A combination flatiron and clothes dampener comprising an iron body, a handle carried by said iron body, said handle being of hollow construction, a spray nozzle at one end of said handle, a water reservoir at the other end of said handle, a tubular connection extending from said water reservoir through said handle to the spray nozzle, a pump housed within the end of said handle adjacent said water reservoir and operable to force water through said tubular connection, an operating member carried by the handle at the end adjacent said spray nozzle, and operating connections between said operating member and said pump, said operating connections being housed within said handle.

4. A combination flatiron and clothes dampener comprising an iron body, a handle carried by the iron body, a spray nozzle at one end of said handle, a water reservoir having a wall formed with an opening, a tubular member extending through said opening and having an inlet within said water reservoir, means for clamping said tubular element to the wall of said reservoir about said opening, said tubular element extending through said handle to the spray nozzle, a pump cylinder defined by a cylindrical wall that is spaced from and disposed about said tubular member, said pump cylinder having a closed end, a ring-like piston enclosing said tubular member and movable in said pump cylinder, spring means normally maintaining said piston in spaced relation with respect to the closed end of said cylinder, and an operating member for moving said piston in said cylinder against the influence of said spring means.

5. A combination flatiron and clothes dampener, comprising an iron body having an ironing face including a nose and a heel, a spray nozzle arranged adjacent said nose, a water reservoir arranged at said heel and having a flat wall inclined to said ironing face and adapted to support said iron body in an elevated position, a handle interposed between said nose and heel and carried by said iron body, a tubular connection extending between said spray nozzle and said reservoir, a pump associated with said tubular connection to force water from said reservoir to said spray nozzle, and a one-way check valve arranged in said spray nozzle and adapted to maintain a column of water in said tubular connection during periods of time when said iron body is resting in an elevated position.

PATRICK J. FITZGERALD.
